UNITED STATES PATENT OFFICE.

ANTHON W. PUTMAN-CRAMER, OF BROOKLYN, NEW YORK.

METHOD OF PRODUCING GAS.

SPECIFICATION forming part of Letters Patent No. 470,007, dated March 1, 1892.

Application filed August 25, 1891. Serial No. 403,657. (No model.)

To all whom it may concern:

Be it known that I, ANTHON W. PUTMAN-CRAMER, a citizen of the United States, residing in Brooklyn, Kings county, and State of New York, have invented certain new and useful Improvements in the Method of Producing Gas, of which the following is a specification, reference being had to the accompanying drawings.

10 My invention relates especially to and has for its object an economical method of manufacturing gas wherein decomposed steam exposed to the presence of carbon is a prominent ingredient.

15 The invention consists in effecting the combustion of a mass of carbon or carbonaceous material or fuel in one chamber, in combining in controlled quantities within a special heated intermediate mixing-chamber a new 20 supply of air with the carbonic oxide arising from the combustion of said mass of carbon and passing said combined air and carbonic oxide to the bottom of and up through a mass of carbon inclosed in a third chamber to assist 25 in its heating and combustion, and finally in passing steam at high temperature through both of said masses of carbon while in a state of incandescence to effect a complete decomposition of said steam.

30 In the accompanying drawings, Figures 1 and 2 represent outside elevations of a furnace within which may be operated and accomplished my improved method of producing gas. Fig. 3 represents a vertical section, 35 and Fig. 4 a horizontal section, of the same.

The structure is preferably built of fire-brick or like refractory material inclosed in sheet metal after any of the ordinary methods.

Similar letters of reference designate like 40 parts or portions in all the figures.

Letter A designates the complete furnace, comprising within its inclosure chambers B, B', and B², chambers B and B² having grates b and b², located to support the fuel-carbon or 45 carbonaceous material through which the steam is to be passed when in an incandescent state.

B' designates an intermediate chamber inclosed between the adjacent walls a and a' of 50 the two chambers B and B², into and through which, by means of passage d, the carbonic oxide arising from the heating and combus-

tion of the carbon contained in chamber B is passed as developed. Into this chamber B' a new and controlled supply of air is passed at 55 c, to be mixed with the contained carbonic oxide as it moves through, thereby effecting its ignition and burning. From chamber B' the burning gases are passed to the bottom of chamber B², through passage d', up through 60 the grate b² to heat and ignite the carbon or carbonaceous material placed upon said grate, assisting materially in the raising of the temperature of said carbon within chamber B² to that necessary for the reliable decomposition 65 of the steam and effecting considerable economy in both time and fuel required. To effect a proper and economical combustion and incandescence of the carbon or carbonaceous material within chamber B², it is necessary to 70 pass the draft or gases in an upward direction. With the gases of combustion from the first mass of carbon in chamber B forced to pass in a downward direction through the second mass of carbon in chamber B², a serious 75 trouble is met with in the constantly-increasing mass of ashes or incombustibles accumulating at the top of said second mass of carbon. Hence the necessity that communication should be opened between the top of the 80 first mass of carbon within chamber B and the bottom of chamber B². The mixing-chamber B' effects such communication. Again, without a controlled admission of new air to the carbonic oxide and a thorough mixing of 85 the two its economical ignition and combustion would be doubtful and uncertain. To facilitate this mixture of admitted air with the carbonic oxide while passing through intermediate chamber B', side jets or tuyeres c 90 are located at its admission end to force the air to pass directly across and at right angles to the path of the carbonic oxide, and, when mixed, out with it through passage d'.

For the admission of air for combustion purposes an air-supply pipe C connects through a valve C' with one or more branch pipes C² for its admission to the space below the grate at the cleaning of openings k k of chamber B and with special branch pipe C³, valve C⁴, and 95 connecting branches C⁵ for its admission to the intermediate chamber B' through the jets or tuyeres c c, located on each side of said chamber B'. For the exit of the products of 100

combustion an uptake or chimney D is provided with a valve d^2 at its top end for the opening or closing of the same. For the passage of the manufactured gas out from chamber B² a branch E is made in this same uptake or chimney D, whereby when the valve d^2 is closed a free exit of said gas is provided for. To admit steam for decomposition, a supply-pipe F connects through valve F' and branch pipes F² with the several connecting-jet branches e e e, through which it passes to the spaces below the grates of each of the carbon-chambers B and B². While the two masses of carbon in chambers B and B² are reaching the necessary state of incandescence the valve d^2 of the uptake or chimney D is kept open and the products of combustion allowed to pass out. With the raising of the carbon to an incandescence or to a temperature sufficiently high for a successful decomposition of the steam the admission of air is shut off and the chimney-valve d^2 is closed tight. The steam to be decomposed is then admitted to the bottom of both chambers B and B². That admitted to the bottom of chamber B passes up through the incandescent carbon in chamber B, thence down through the intermediate chamber B' to mingle with the steam admitted to the bottom of chamber B² and with it to pass up through the incandescent carbon of chamber

B² for continued decomposition, whence it passes out through D and E, valve d^2 being closed. When the two masses of carbon become too cool for decomposition uses, the steam is shut off and combustion-drafts and air-admission resumed.

What I claim as new, and desire to secure by Letters Patent, is—

The improved method of producing gas through the intermingling of steam or water vapor with carbon, which consists in effecting the combustion and incandescence of a first mass of carbon within its inclosing chamber, in combining within a special intermediate chamber a new supply of air with the carbonic oxide arising from the combustion of said first mass of carbon, igniting and passing said combined air and carbonic oxide to the bottom of and upwardly through a second inclosed mass of carbon to effect its incandescence, and in simultaneously passing steam upwardly through both of said incandescent masses of carbon to effect its decomposition and widespread exposure to the heated carbon, substantially as set forth.

ANTHON W. PUTMAN-CRAMER.
